(57) **CLAIM**

The ornamental design for a display screen with animated graphical user interface, as shown and described.

DESCRIPTION

FIG. 1 is a first image in the sequence for an animated image of a display screen with an animated graphical user interface showing our new design;

FIG. 2 is a second image thereof; and,

FIG. 3 is a third image thereof.

The appearance of the animated image sequentially transitions between the images shown in FIGS. 1-3. The process or period in which one image transitions to another forms no part of the claimed design.

The outer broken lines illustrate the display screen. The remaining broken lines illustrate portions of the graphical user interface. None of the broken lines form part of the claimed design.

1 Claim, 3 Drawing Sheets
